UNITED STATES PATENT OFFICE.

AUGUST E. NIENSTADT, OF NEW YORK, N. Y., ASSIGNOR TO MAURICE WOLFER, OF NEW YORK, N. Y.

COLOR-CARTRIDGE.

1,155,676.

Specification of Letters Patent.

Patented Oct. 5, 1915.

Application filed May 27, 1913, Serial No. 770,247. Renewed March 1, 1915. Serial No. 11,325.

To all whom it may concern:

Be it known that I, AUGUST E. NIENSTADT, a citizen of the United States, residing at New York, in the county of New York and 5 State of New York, have invented certain new and useful Improvements in Color-Cartridges, of which the following is a specification.

My invention relates to a coloring cartridge for use in supplying ink-wells, reservoirs of fountain pens, stylographic pens and ink pencils, and for distributing laundry blue and the like.

One of the objects of the invention is to 10 provide a cartridge which will supply the maximum amount of color.

A further object of the invention is to provide a cartridge which may be used in various forms and shapes, to permit of its 20 being employed in conjunction with a fountain pen or an ink-well, or as a laundry blue distributor, with equal facility.

A still further object of my invention is the provision of a cartridge which is simple, clean, convenient and economical, and 25 in which the nucleus or body portion will not disintegrate to form pulp or like substance.

To the accomplishment of the recited objects and others coördinate therewith, the preferred embodiment of my invention resides in that construction and arrangement 30 of parts hereinafter described, illustrated in the accompanying drawings, and embraced 35 within the scope of the appended claims.

In said drawings, Figure 1 is an elevation of a piece of string previous to its being saturated with the coloring material. Fig. 40 2 is a similar view of the string after it has been saturated. Fig. 3 is a transverse sectional view taken along lines 3—3 of Fig. 2. Fig. 4 is a perspective view illustrating one of the forms into which the cartridge 45 may be arranged, and Fig. 5 is a similar view of another form.

In the drawings, the numeral 1 designates a piece of string or cord of any desired length and composed of loosely twisted fibers. This string is immersed in any suitable coloring fluid and allowed to remain a time sufficient to permit the fluid to thoroughly permeate and saturate all of the fibers. Subsequently, the string is removed from the bath and allowed to dry whereupon 55 it is cut into short lengths of any desired

longitudinal extents, as exhibited in the drawings. Manifestly, this method of forming the cartridges may be reversed—that is to say—the string may be initially cut to form a plurality of shorter strings which can then be subjected to the coloring treatment. It will also appear obvious that a wick or any other equivalent device involving a plurality of loosely arranged fibers will act in the same capacity as a nucleus. 60

As will be seen upon inspection of Figs. 2 and 3, the coloring matter 2 adheres to the exterior portion as well as permeates the innermost interstices of the fibers, and by reason of the relatively large amount of 65 color carried by the string, it will appear evident that when combined with water the maximum quantity of coloring fluid will be supplied. When dry the color imparts a certain stiffness and rigidity to the fibers 70 which maintains them straight or distended so that they may be readily inserted into a fountain pen or other small reservoir. At the same time this stiffness will not interfere with the flexibility of the cartridge. As 75 shown in Fig. 4, the cartridge may be tied in a knot, as 3, and thus be easily accommodated by any ink-well or the like. Or, as illustrated in Fig. 5, the cartridge may be made in the form of a loop 4 with its 80 extremities stuck or otherwise fastened, as at 5, to a holder 6. This device may be used as a laundry blue distributor.

Another important advantage possessed by my invention is that the fibers will not 85 disintegrate and form a pulp which will clog or injure a fountain pen.

It should be understood that in its broader aspect the invention comprehends the employment not only of the various means 90 described, but of equivalent means for performing the recited functions. While the arrangement shown is thought at the present time to be preferable, it is desired to reserve the right to effect such modifications 95 and variations thereof as may come fairly within the scope of the appended claims.

What is claimed, is:—

1. A color cartridge in the form of a string composed of a multiplicity of loosely 105 arranged threads saturated and coated with readily soluble coloring matter.
2. A color cartridge in the form of a flexible string composed of a multiplicity of loosely arranged flexible strands satu- 110

- rated with a readily soluble coating material.
3. A color cartridge in the form of a string composed of a multiplicity of loosely arranged threads saturated and coated with readily soluble coloring matter, and having inherent rigidity to retain its distended condition.
4. A color cartridge in the form of a string composed of a multiplicity of longitudinally arranged strands saturated with and rendered stiff by a readily soluble coloring material.

5. A color cartridge in the form of a string composed of a multiplicity of longitudinally arranged strands saturated with and rendered stiff by a readily soluble coloring material, and a holder to which said string is attached and beyond which it projects.

In testimony whereof I affix my signature in presence of two witnesses.

AUGUST E. NIENSTADT.
